UNITED STATES PATENT OFFICE.

SETH WILLIAM BABBITT, OF MERIDEN, CONNECTICUT.

SHAVING-CUP.

SPECIFICATION forming part of Letters Patent No. 686,502, dated November 12, 1901.

Application filed June 21, 1901. Serial No. 65,452. (No model.)

To all whom it may concern:

Be it known that I, SETH WILLIAM BABBITT, of Meriden, in the county of New Haven and State of Connecticut, have invented a new and useful Improvement in Shaving-Cups; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a cup constructed in accordance with my invention; Fig. 2, a top view of the cup with the soap-holder removed; Fig. 3, a top or plan view of the soap-holder detached; Fig. 4, a vertical central section through the cup and soap-holder.

This invention relates to an improvement in shaving-cups, and particularly to that class which comprises a water-cup and a receptacle for soap, the object of the invention being to so combine the soap-holder and cup that access may be had to the interior of the cup while the soap-holder is supported in the upper end of the cup and to provide for the complete ventilation of the cup; and the invention consists in the construction as hereinafter described, and particularly recited in the claim.

The cup A, as herein shown, is rectangular in transverse section and is adapted to support a rectangular soap-holder B. As herein shown, the four sides of the cup are outwardly bowed, forming V-shaped corners or grooves C at each corner, which form bearings for the four corners of the soap-holder. One side D of the holder is set inward into substantially semicircular form, which side forms a free clearance-opening E for the brush to be passed into the cup A, while at each of the other sides of the holder an opening is provided into the cup, permitting a free circulation of air. This holder being angular may be turned so as to present its inset side toward either side of the cup, whereby the passage to the cup for the brush may be at

any convenient point with relation to the handle. As herein shown, the cup is provided with a handle E' and the soap-holder with a brush-support F, which features, however, form no part of this invention.

It is apparent that instead of forming the soap-holder substantially rectangular and the cup with four grooves or corners, into which the holder may fit, the holder might be of other angular form and the cup correspond to receive it, the essential feature of my invention being an angular holder in connection with a cup having outwardly-bowed sides.

As herein shown, the sides of the cup are tapering, and the sides of the holder correspond thereto; but it is apparent that the sides might be straight and means provided to support the holder in the top of the cup. I therefore do not wish to be understood as limiting the invention to the exact construction shown.

I am aware that round shaving-cups have been provided with soap-holders having an inset side adapted to provide a clearance-entrance for the brush into the cup. I therefore do not wish to be understood as claiming, broadly, such as my invention; but,

Having fully described my invention, what I claim as new, and desire to secure by Letters Patent, is—

In a shaving-cup the combination with an angular cup having outwardly-bowed sides forming a shaped groove at each corner of the cup and an angular soap-holder adapted to set into the said cup, the corners of the holder entering the grooves in the cup, said holder inset at one side coacting with one side of the cup to form a brush-opening, the other sides of the holder coacting with the other bowed sides of the cup to form passages into the cup substantially as described.

In testimony whereof I have signed this specification in the presence of two subscribing witnesses.

SETH WILLIAM BABBITT.

Witnesses:

CARL F. SORG,
JAMES B. BARNES.
